C. BELDIN.
PUMPING MEANS FOR GAS APPARATUS.
APPLICATION FILED FEB. 4, 1915.

1,175,115.

Patented Mar. 14, 1916.

UNITED STATES PATENT OFFICE.

CARSON BELDIN, OF BERLIN, MARYLAND.

PUMPING MEANS FOR GAS APPARATUS.

1,175,115.

Specification of Letters Patent. Patented Mar. 14, 1916.

Application filed February 4, 1915. Serial No. 6,125.

To all whom it may concern:

Be it known that I, CARSON BELDIN, a citizen of the United States, and a resident of Berlin, in the county of Worcester and State of Maryland, have invented certain new and useful Improvements in Pumping Means for Gas Apparatus; and I do hereby declare the following to be a full, clear, and exact description of the invention, such as will enable others skilled in the art to which it appertains to make and use the same.

This invention relates to improvements in gas apparatus and more particularly to such as is adaptable for use in generating and regulating carbureted air for lighting and heating purposes.

One object of the invention is to provide a simple and efficient apparatus for generating and controlling the supply of gas for domestic use, the plant being such as can be installed in rural districts or places beyond the reach of city gas supply systems.

With this and other objects in view, the invention consists in certain novel features of construction and combinations of parts as hereinafter set forth and pointed out in the claims.

The accompanying drawing is a view partly in section, illustrating my improvements.

1 represents a tank which may be conveniently supported upon legs 2, and within said tank 1 and concentric therewith, another tank 3 is located,—said tanks being spaced apart to form a water chamber 4 between them.

Located centrally within the tank 3, is a pump cylinder 5, the lower end of which is provided with a pipe 6 secured to and passing through the bottom 7, while said pump cylinder is supported in an upright position by braces 8 extending therefrom to the wall of the tank 3. A piston 9 is closely fitted within the cylinder 5 so as to have water-tight contact with the wall thereof, and to this piston, a piston rod 10 is secured. The piston rod 10 passes through a suitable stuffing box at the upper end of the cylinder and at its upper end, it is secured to the top 11 of an inverted cylinder or bell 12, the ver-

tical wall of which latter dips into the water chamber 4 between the tanks 1 and 3.

A pipe 13 (which receives water under pressure from any convenient source of supply) communicates with the pipe 6 to supply water under pressure to the lower end of the pump cylinder under the piston therein.

A short tube 14 is secured to and passes through the bottom 7 so as to communicate at its upper end with the air chamber 15 formed within the tank 3 and the bell 12, the lower end of said tube being open. The admission of air to the chamber 15 is controlled by a counterweighted valve 16 mounted within said chamber and adapted to seat upon the upper end of the tube 14. A pipe 17 communicates with the lower portion of the air chamber 15 and extends to and communicates with a suitable carbureter 18,—a check valve being located in the circuit of this pipe as indicated at 19. At a suitable point in this pipe, near the carbureter, an air vent 20 is provided.

A pipe 21 communicates with the carbureter and is provided with a capped inlet 22 for gasolene for charging the carbureter. This pipe also constitutes the outlet for carbureted air and with it, one end of a pipe 23 is connected, the other end of said pipe 23 being connected with a mixer 24 of suitable construction. A gas supply pipe 25 communicates with the mixer for conducting the gas to the point or points of consumption. To provide ready means for supplying air to be mixed with the gas coming from the carbureter, a pipe 26 is connected at one end with the air pipe 17 and at the other end with the inlet end of the mixer. A counterweighted valve 27 is provided in the mixer for automatically controlling the admission of air to the mixer through the pipe 26.

A pipe 28 communicates with the upper end of the pump cylinder 5, and has connected thereto, by means of a coupling 29, a pipe 30, which latter extends downwardly through the bottom 7 of the apparatus. A pipe 31 is connected, through a coupling 32, with the pipe 30, and said pipe 31 is connected with a pipe 33. One end of the pipe 33 is connected with the pipe 17 at a point

beyond the check valve 19 and the other end of said pipe 33 is made with an air inlet controlled by a check valve 34. A check valve 35 is also located in the pipe 33 between the connections of said pipes with the pipes 17 and 30.

A valve 36 is located in the water pipe 13 and the casing of this valve is provided with a discharge outlet 37 to permit the discharge of water from the pump cylinder when the valve 36 is closed during the descending movement of the piston. The rod of the valve 36 is connected with a pinion 38 in such manner that rotation of the latter will effect the opening or closing of the valve. A rack bar 39 meshes with the pinion 38 and is carried by a rod 40 movable in guides 41. Springs 42 are mounted on the rod 40 and each is connected at one end to said rod. A rod 43 is carried by and movable with the bell 12 and this rod is provided at its lower end with an arm 44 movable on the rod 40 between the springs on the latter.

When the valve 36 is open, water, under pressure, will enter the lower end of the cylinder 5 and force the piston 9 upwardly, thus raising the bell 12 and causing the filling of the air chamber through the valved inlet tube 14. At the same time, the air in the cylinder 5 above the piston will be forced out through the pipes 28-30-31 and 33 to the air pipe 17 and thence to the carbureter. Means are thus provided for effecting the continuity of the air supply to the carbureter while the air chamber 15 is filling with air during the rising movement of the bell 12.

When the bell 12 reaches the upper end of its movement, the arm 44 will engage the upper spring 42 on the rod 40 and thus raise said rod in such manner as to cause motion to be imparted by the rack bar 39 to the pinion 38 and effect the closing of the valve 36 in the water pipe. The bell may now descend by gravity, the water in the cylinder 5 escaping through the discharge outlet 37 and the air passing from the chamber 15 out through the pipe 17 to the carbureter. During the descent of the piston 9, air will be drawn into the pump cylinder through the check valve 34, and pipes 31-30-28, the check valve 35 being, at this time, closed. When the bell reaches the lower end of its movement, the arm 44 will engage the lower spring 42 on rod 40 and cause a downward movement of said rod, which will effect the opening of the valve 36 in the water pipe, as will be readily understood. Power will now be again supplied for raising the pump piston 9 and the bell 12 and the cycle of operations above described will be repeated.

In order to prevent the water in the chamber 4 from freezing, a heating coil 45 may

be provided. This coil may be inclosed in a 65 casing 46 containing a suitable heating burner 47, and said coil is connected at its respective ends with the water chamber 4. A spigot 48 may be connected with the water chamber, for discharging the water 70 therefrom when desired.

Various changes might be made in the details of construction of my invention without departing from the spirit thereof or limiting its scope, and hence I do not wish 75 to restrict myself to the precise details herein set forth.

Having fully described my invention what I claim as new and desire to secure by Letters-Patent, is:

1. In apparatus of the character described, the combination with concentric tanks forming a water chamber between them and a bell having its wall immersed in said water chamber, said bell and the inner tank forming an air chamber, of a cylinder in said air chamber, a piston in said cylinder connected with said bell, a valve controlled air inlet for said chamber, an air pipe for conducting air from said chamber to a carbureter, means connecting the upper end of the cylinder with said air pipe, and a check valve between said pipes.

2. In apparatus of the character described, the combination with concentric tanks forming a water chamber between said tanks, and a bell having its wall immersed in said chamber and cooperating with the inner tank to form an air chamber, of a cylinder, a piston in said cylinder connected with said bell, valved inlet for said air chamber, a pipe for conducting air from said chamber to a carbureter, a check valve in said pipe, a pipe communicating with the upper end of the cylinder, an intermediate pipe communicating with the first-mentioned pipe and the last-mentioned pipe, a check valve in the intermediate pipe between its connection with the other pipes, said intermediate pipe having an air inlet, and a check valve controlling said inlet.

3. In apparatus of the character described, the combination with an air pump, and a water operated pump for operating the air pump, of an air pipe for conducting air 115 from the air pump to a carbureter, means for conducting air from the water operated pump above the piston of the latter to said air pipe, and means for controlling the operation of the water operated pump.

4. In apparatus of the character described, the combination with an air pump, and means for conveying air from the air pump to a carbureter, of a cylinder, a piston in said cylinder connected with the movable 125 member of the air pump, an inlet valve for the air pump, an air pipe for conducting air from said pump to a carbureter, a water

pipe connected with the cylinder under the piston therein, a valve in said pipe, means operated by the air pump for opening and closing said valve, and means for conducting air from the upper portion of the cylinder to said air pipe when the movable member of the air pump ascends.

In testimony whereof, I have signed this specification in the presence of two subscribing witnesses.

CARSON BELDIN.
